UNITED STATES PATENT OFFICE

151,687

DESIGN FOR A COMBINED LAMP AND SMOKING STAND

Earl R. Fisk, Depew, Okla.

Application October 28, 1947, Serial No. 142,172

Term of patent 3½ years

(Cl. D48—20)

To all whom it may concern:

Be it known that I, Earl R. Fisk, a citizen of the United States, residing at Depew, in the county of Creek and State of Oklahoma, have invented a new, original, and ornamental Design for a Combined Lamp and Smoking Stand, of which the following is a specification, reference being made to the drawing forming a part thereof.

Figure 1 is a perspective view of a combined lamp and smoking stand, showing my new design, and

I claim:

The ornamental design for a combined lamp and smoking stand, as shown.

EARL R. FISK.
